UNITED STATES PATENT OFFICE

2,333,900

FOOD STORAGE AND DISPLAY DEVICE

Edward M. Stiles, Burlington, Iowa

Application December 1, 1941, Serial No. 421,165

6 Claims. (Cl. 62—89.6)

My invention relates to apparatus for the storage, preservation and display of food stuffs. More specifically, it relates to a cabinet having a plurality of storage compartments, isolated from each other and from the refrigerating coils so far as air movement is concerned, and provided with doors or slides through which the contained goods may be seen and which may be opened for convenient access.

An object of my invention is to provide means for the storage of food stuffs such as fresh fruits and vegetables, whereby troubles from dehydration and mold formation can be eliminated.

A further object is to provide storage means in which high humidity and low temperature can be maintained when desired, to keep vegetables in crisp condition and even to restore crispness to vegetables which have become wilted or dried in shipment.

Another object is to provide a storage and display cabinet with individual compartments so arranged that obtaining access to any one compartment does not involve loss of cold air from adjacent compartments.

A further object is to provide food storage means of the kind described with individual compartments having horizontally extending shelves forming baffles which limit the cross sectional area of the storage space, with consequently reduced convection circulation.

Still another object is the provision of storage means in which the contained goods are clearly visible and readily accessible to the customer or sales person.

With these and other objects in view, my invention consists in the construction, arrangement and combination of the various parts of my device whereby the objects contemplated are attained, as hereinafter more fully set forth, pointed out in my claims and illustrated in the accompanying drawings, in which:

Figure 1 is a front elevational view of a storage and display cabinet embodying my invention.

Figure 2 is a horizontal cross sectional view taken on the line 2—2 of Figure 1.

Figure 3 is a vertical sectional view on the line 3—3 of Figure 1.

Figure 4 is a fragmentary vertical sectional view taken on the line 4—4 of Figure 3.

Figure 5 is a perspective view showing a possible type of construction for the assembly of the individual compartments.

Figure 6 is a perspective view of a sliding closure panel.

In the drawings I have used the reference nu-

merals 10 to indicate generally an outer cabinet having walls of insulating material as is customary with refrigerated display cabinets. A refrigerating coil 12 is provided in the top of the cabinet in the usual manner. Mounted within the cabinet are individual compartments C which for convenience may be assembled on a rack or framework 14 so that they can be installed or removed in the cabinet 10 as a single unit.

10 The compartments C are preferably constructed of sheet metal or any material having good heat conductive qualities. They are mounted in such a manner that substantial space is provided between adjacent compartments, and 15 above, below and behind the compartments so that the air in the cabinet cooled by the refrigeration coil 12 may circulate freely and have access to all sides of the compartments except at the front. The front edges of the compartments 20 are preferably connected by a panel 16 through which each compartment opens individually. In the unit assembly suggested, the panel 16 may conveniently be attached to the supporting framework 14 so that it forms a part of the assembly. When the assembly is inserted in the casing 10 it rests on horizontal supporting members 18 and the panel 16 makes a sealing engagement around all of its edges, as indicated, for example, at 20 and 22 in Figure 2, and 24 and 26 25 in Figure 3. With the panel fitted in this way, there can be no substantial escape from the cabinet of the air which circulates over the coil 12.

30 The unit assembly which I have described 35 greatly facilitates cleaning or repair of the cabinet. If a drain clogs up or if refrigerating coils or connections need attention, access is relatively easy, without any necessity for dismantling operations which might mar or damage the cabinet.

40 The front of the cabinet is provided with sliding doors indicated generally by the numeral 28. These doors may be mounted for sliding operation in ways well known in the refrigerator cabinet art. To minimize heat leakage they are preferably provided with multiple glass 30 as shown in Figures 2 and 3. The advantages of my invention are more readily attained if one such door is provided for each compartment C so that cold air is lost from only one compartment when a door is opened.

45 I have found that proper storage conditions for fruits, vegetables and meats as met in the usual grocery store must involve among other things

the provision of a suitable low temperature, high humidity and minimum air circulation.

As regards the requirement of low temperature, it will be understood that any desired temperature may be reached by suitable adjustment of the refrigerating equipment supplying the coil 12. For proper storage of fruits and vegetables, I find a temperature in the range of 34° to 38° F. to be desirable; for meats, a slightly lower temperature is preferable. With conventional food storage cabinets the maintenance of such low temperatures has involved relatively high circulation velocities, and attendant rapid dehydration of the foods, the moisture absorbed from the foods by the rapid current of air being lost by deposit on the refrigerating coils.

The dehydration problem is so serious that as a matter of practical fact all refrigerated grocery cases for fresh goods, so far as I am aware, are operated at temperatures higher than what I have recommended. At the higher temperatures the velocity of air circulation is lower, and the humidity of the air is higher. Dehydration troubles are reduced, but along with the higher temperatures and higher humidity come mold and decay.

An important contribution to the effectiveness of my apparatus, however, results from the fact that five walls of each compartment are exposed to the cold air circulating over the coil 12, so that there is a large amount of conducting surface with relation to the volume of the compartment. With this large conducting area, the desired temperature can be maintained within the compartment with only a very moderate differential in temperature between the average compartment temperature and the wall temperature. This low differential coupled with the fact that refrigeration takes place on five sides of the compartment makes for very low velocities of convection circulation. Furthermore, the location of the adjacent compartments is such that heat may be readily interchanged between them. For example, when any compartment is newly loaded up with warm goods, the adjacent compartments act much like blocks of ice on each side, quickly cooling the new goods. Similarly, when a compartment is opened at the time a sale is made, some cold air will be lost but the temperature in the compartment will be quickly brought down to the desired point again by heat transfer to adjacent compartments as well as to the circumambient air.

With regard to maintaining the proper humidity, the first feature of importance is that the interior of each compartment is isolated from the air circulating over the coil 12 so that the air in the compartment is not dehydrated by the usual deposit of moisture on the coil. The large surface area of the compartments makes possible adequate refrigeration without a wall temperature so low as to cause excessive condensation. Hence, as a practical matter it is possible to maintain any ordinary degree of humidity which is desired within the compartment. When higher than normal humidity is wanted, the vegetables may simply be sprinkled or sprayed with water. This may be necessary with goods which have just been put into the cabinet, after having dried out somewhat in previous shipment or storage. Even vegetables freshly picked from the garden during a dry spell may be improved by storage at low temperature and high humidity. They absorb moisture, become more crisp and appetizing, and cook faster.

With regard to air circulation, I have found it advantageous to restrict the cross section of storage space through which convection circulation can take place to a value which may be stated roughly as a maximum of about 200 square inches. Where the apparatus illustrated in my drawings represents a commercial size display case, I have found it desirable to break up the space within the compartments. The individual compartments themselves may conform to this specification, or where the compartments are larger the space within them may be broken up by providing horizontal shelves 32 which serve as baffles to reduce the uninterrupted cross sectional area below the approximate value indicated. In the cross sectional view of Figure 4, for example, the portions A and B into which the compartment is divided by the shelf 32 are each of less than 200 inches cross sectional area. Furthermore, the provision of a shelf of this kind facilitates the neat display and convenient accessibility of numerous different kinds of produce. The shelf may rest loosely on support 33, so that it can be easily removed to facilitate cleaning of the compartment.

Limitation of the cross-sectional area has the further effect that no part of the interior of the compartment, when made as shown in the drawings, can be more than a certain distance from a refrigerated wall. For example, if the portions A and B in Figure 4 have the maximum area of 200 square inches, no part of one of these portions can be more than about 14 inches from a refrigerated wall. This makes for uniformity of temperature conditions throughout the compartment.

Obviously, no critical limiting figure for cross section can be assigned. In actual tests, however, I have found that even at 200 square inches when the compartments are only a third to a half full there will be enough freedom of circulation to cause slight dehydration. On the other hand, with the compartments packed full there may be a little trouble with "moldy center"—mold or decay taking place in the foodstuffs in the center of the compartment, farthest from the cold walls.

With a cross section of 160 square inches, there was no trouble with dehydration or with moldy center.

It will be understood, therefore, that I have provided a construction whereby it is possible to attain the essential conditions for the best preservation of fruits, vegetables and meats, as follows:

1. Uniform temperature, low enough to prevent mold, decay, growth and slime.
2. Moist air, preferably at the dew point, containing more moisture than the stored products.
3. Minimum circulation of air over the products.

Particularly for use in self-serve stores, my apparatus has the advantage that it keeps fruits and vegetables in first class condition, yet perfectly visible to the public in such a way that ready and immediate access may be had to the items which the customer sees.

Carelessness on the part of a customer or salesperson in leaving a compartment open will have no serious effect on the adjacent compartments or on the goods stored therein.

Some changes may be made in the construction and arrangement of the parts of my device without departing from the real spirit and purpose of my invention, and it is my intention to cover by my claims any modified forms of struc-

ture, or use of mechanical equivalents, which may be reasonably included within their scope.

I claim as my invention:

1. Refrigerated storage means comprising a plurality of spaced-apart compartments having walls of conducting material, disposed within a refrigerated casing, and baffles within said compartments so arranged that at any place within the compartment a vertical cross section on a plane transverse to the length of the compartment will have not more than 200 square inches of area throughout which unrestricted convection circulation may take place.

2. In a food storage and display cabinet, a refrigerated casing, and independent compartments therein, each of said compartments being arranged so that a vertical cross section transverse to the length of the compartment has not more than 200 square inches of area throughout which unrestricted convection circulation can occur.

3. In food storage and display means, a refrigerated cabinet, a plurality of compartments therein, said compartments having walls of conducting material, being exposed to refrigeration on top, bottom and sides, and opening individually to the outside of said cabinet, and means in each compartment whereby the maximum area throughout which unrestricted convection circulation may take place, on a vertical cross section transverse to the length of the compartment, is limited to approximately 175 square inches.

4. A self-serve food merchandiser including an outer heat-insulated casing, refrigerating means therein, a plurality of metal-walled compartments in said casing, means whereby the open-

ing of each compartment is isolated from air circulating over the refrigerating means, individual windowed closures for each compartment, and means in each compartment limiting the maximum area throughout which unrestricted convection circulation can take place, on a vertical cross section transverse to the length of the compartment, to approximately 175 square inches.

5. A self-serve food merchandiser including an outer heat insulated casing, refrigerating means therein, a plurality of compartments mounted on a rack for installation in and removal from said casing as a single unit, said compartments having walls of conducting material and being spaced apart on said rack so that each compartment is exposed to refrigeration on top, bottom and sides, means whereby the opening of each compartment is isolated from the air circulating over the refrigerating means, individual doors for each compartment, and windows in said doors through which the goods in said compartments may be seen.

6. In food storage and display means, a refrigerated cabinet, and a plurality of compartments therein having walls of conducting material, said compartments being exposed to refrigeration on one end, top, bottom and sides and being of such shape and size that no point in the interior of a compartment is more than fourteen inches from one of said refrigerated conducting walls, an individual door in each compartment opposite said one end, and a window in each door through which the goods in the compartment may be seen.
